(57) CLAIM

The ornamental design for a sole plate for a golf club head, as shown and described.

DESCRIPTION

FIG. 1 is a bottom perspective view from the toe side of a golf club head showing the sole plate of our new design.

FIG. 2 is a bottom perspective view from the heel side thereof.

FIG. 3 is a bottom plan view thereof.

FIG. 4 is a front view thereof.

FIG. 5 is a rear view thereof.

FIG. 6 is a toe side view; and,

FIG. 7 is a heel side view.

The broken lines in the drawings are for the purpose of showing environmental structure and do not form part of the design to be patented.
